DEVICE FOR STRETCHING AND FOR
FORMING THE RIMS OF SPECTACLES

Alexander Horvath, Chicago, Ill.

Application December 18, 1948, Serial No. 66,008

6 Claims. (Cl. 81—3.5)

1

This invention relates to an improvement in a device for stretching and/or forming the rims of spectacles.

One of the objects of this invention is to provide an improved device for stretching and/or forming the frames or rims of plastic spectacles, and is an improvement over my Patent No. 2,552,043 issued May 8, 1951.

Another object of this invention is to provide a spectacle rim stretcher which will shape and/or stretch the rims without leaving any impressions or marks on the spectacles thus treated.

Another object is to provide a device of the foregoing character which will effectively and securely lock the stretching cone to the heating unit during the operating and forming period.

This invention (as that of the aforesaid pending application) eliminates the necessity of maintaining a number and variety of rim stretchers, as now commonly employed where there is one for each shape, as well as rights and lefts of the frame.

Other objects will become apparent as this description progresses.

In the drawings:

Fig. 1 is an exploded perspective view showing the preferred form of my device used in connection with a heating unit, part of which is shown in cross section and also showing the means for locking the stretching cone to the heating unit.

Fig. 2 is a fragmentary view showing one of the lugs in locked position for securing the cone to the heating unit.

Fig. 3 is an enlarged perspective view showing two segments of the segmentally formed stretching cone.

Fig. 4 is a cross sectional view taken on line 4—4 of Fig. 3.

Fig. 5 is a perspective view of a modified form of construction showing the stretching cone made of a continuous uninterrupted wall and showing the pattern thereon in the position it would be placed on the cone when the pattern is locked to the heating unit.

Fig. 6 is a view taken on line 6—6 of Fig. 5.

Fig. 7 is a perspective view of a modified form of construction utilizing screening material for the stretching cone.

In the construction shown in Fig. 1, the truncated cone shaped device, generally indicated at 10 shall hereinafter be referred to as a stretching cone or a forming cone and is described in detail in my copending application, Serial No. 10,074, filed February 21, 1948. It will be briefly described herein. It is formed of a plurality of segments or ribs 12 interlocked or interlaced to-

2

gether as at 14 to form a continuous wall and providing a pivoted or hinged connection between each segment or rib to permit the cone to be sufficiently flexible on the transverse cross section so that it may be reshaped transversely. All the segments 12 are identically formed and identically interlocked and a description of one will suffice.

The rib or segment 12 is an elongated member 10 having an adjoining front wall 16 and side wall 18 positioned at right angles to each other. The front wall gradually tapers outwardly from the top 20 to the bottom 22 and the measurement of the front wall at the top is about two-thirds of the measurement at the bottom. The front wall is curved on its transverse cross section as at 21, best shown in Fig. 4. Spaced from the top of the front wall is an inverted L shaped extension 24 which is formed at right angles to the front wall 16 and is substantially parallel to the side wall 18. Between the leg 26 of the extension and the front wall 16 there is a space 28 which permits interlocking of the segments, as will presently be described.

25 Along the juncture 30 of the adjoining front and side walls there is an elongated slot 32 which extends from above the extension 24 to approximately the level of the horizontal line 34 of the extension. Adjacent the bottom of the segment, 30 I provide another L shaped extension 36 similar to that previously described, with the leg portion 38 extending slightly below the level of the side walls as at 40. The juncture of the walls is likewise provided with an elongated slot 42, the top 35 of the slot extending above the level of the top of the extension and the bottom of the slot being substantially level with the horizontal line 44 of the extension.

The segments 12 are positioned adjacent each 40 other and interlocked, as best shown in Figs. 3 and 4. To interlace adjoining segments, the bottom L shaped extension 36 is inserted in the slot 42 of the adjacent segment and the top L shaped extension 24 is then inserted in the slot 32 of the adjacent segment. In this condition there is a vertical play between adjoining segments. The adjoining segments are then positioned so that the tops of each are on the same horizontal plane and that portion 40 of the bottom leg 38 which extends below the bottom of the adjoining side is bent at right angles as at 46 to engage the underside of the side wall 18 and prevent any vertical movement between adjoining segments, thus locking the segments to 50 each other to form a continuous wall 48. A

hinging or pivotal connection is provided between adjacent segments to permit the wall 48 of the cone to be sufficiently flexible to permit its reshaping transversely to assume any shape that may be necessary by virtue of the shape of the rims of the frame. The cone automatically takes on the shape of the rim of the frame placed upon it. A piano wire 49 (Fig. 3) passes through all the slots 42 of the cone segments and rests against the inside of the front wall 21 of the segment to keep the segments and the cone expanded or urged outwardly for engagement with the jacket, to be presently described.

Over said cone shaped forming device I place a truncated cone shaped jacket 50, which is preferably made of a thin flexible piece of metal having a continuous wall 52 which may be welded or otherwise secured together as at 54. The jacket 50 is positioned on the forming device 10 to practically cover same. It is permanently secured thereto by a plurality of rivets 54A. The jacket is flexible so that it readily conforms and reshapes itself to the shape assumed by the segmental cone or forming device 10. The lens frame 8 is placed over the jacket 50 so that the inner portion of the rim 9 engages a continuous smooth surface and no marks or impressions will be formed on the rim 9.

The flexible forming device 10 is used in connection with a heating unit. The heating unit, generally indicated at 56 comprises a base 58 on which is positioned and secured in any conventional manner a heating element 60. A housing 62 encloses the heating element. The flange 64 of the housing rests on the base 58. A cap 66 is positioned over the flange 64 and an annular socket member 68 having an annular upright wall 70 is positioned on top of the cap 66. A plurality of rivets 71 passing through said parts secure same to the base. The heating unit has a conducting wire 72 connected to a suitable electrical outlet and a switch 74 operates the heating unit.

The upright annular wall 70 has a pair of diametrically opposed slots 75 and each slot has an inclined slope in an opposite direction to the other. The slots are to receive the lugs 78 on the pattern 76, to be presently described.

The segmental cone 10, together with the jacket 50 is placed on the socket member 68 and surrounds the heating element 60 and housing 62 and is heated thereby. When thus heated, the rim 9 of the frame is positioned on the jacket and the frame 8 is moved downwardly thereon, the segmental cone 10 with the jacket 50 thereon will automatically adjust itself to the shape of the rim 9. The spectacle frame is moved down as far as it is desired to expand and/or stretch the rim. The rim will be stretched uniformly in its preformed shape. When the rim has been expanded to the required size, the operator removes the frame from the cone and jacket, inserts the lens in the rim and places it in cold water to cool, allowing the rim to contract and tightly secure the lens in the frame.

To reshape the rims of frames for providing other styles, I provide a pattern 76 which is first placed on the cone and jacket, as shown in Fig. 1, to reshape the cone and jacket to the shape of the cutout of the pattern. The pattern is slid down on the cone (to a lower position than shown in Fig. 1) as far as possible until it wedges on the jacket and enters the socket member 68, thus reshaping the cone and jacket. The pattern has a pair of diametrically opposed lugs 78 which are

each bent at an angle in the opposite direction from each other and complementally to the angle of the slots 75. The lugs enter the slots 75 in the wall 70, and as the pattern is turned 5 counterclockwise, the lugs ride down the inclined slots and wedge therewith to lock the pattern in said slot. This will secure the cone and jacket to the base of the heating unit and will prevent any loose play therebetween. The rim of the frame 10 is then placed on the cone, as shown in Fig. 1 and reshaped to the shape of the cone which corresponds to the shape of the pattern 76. The size of the reshaped rim being determined by the position it is pushed down on the cone. With 15 this arrangement, only a single pattern is needed for each of the various styles of rim, as the sizes are formed on the cone. While I have shown only one pattern, it will be obvious that other shaped patterns with cutouts shaped to conform to the various styles of rims may be used. The same pattern is used for the right and left rims by turning the pattern over and thus inserting it on the cone. A pattern is used when the shape of the rim of the spectacle is to be altered into 20 another shape or when a much too small rim is to be considerably enlarged.

In Figs. 5 and 6 I show a modified form of stretching device 83 made in the shape of a truncated cone and of a thin flexible metal material 30 having a continuous wall surface, somewhat similar to the jacket 50 previously described. The opposite ends thereof may be welded or otherwise permanently joined as at 82. In this construction the stretching cone is placed on the heating 35 unit like that previously described and is operated in the same manner. However, in this construction no segmental cone is used and the shaping of the rim is done directly on the stretching cone 83. The pattern is shown positioned on the cone at the place it would be positioned when the pattern is locked to the heating unit.

In Fig. 7 I show a construction in which the stretching cone 84 is made of a wire cloth or mesh cloth and the rim 9 of the spectacles is formed 40 directly on the stretching cone 84 in the same manner as previously described. No segmental cone is used.

It will be understood that various changes may be made without departing from the spirit and 45 scope of my invention.

I claim:

1. A device for stretching or reshaping rims of plastic frames of spectacles comprising a substantially conical member capable of being reshaped, a heating unit on which said conical member is positioned and having a locking member, a pattern positioned on said conical member to shape same, said pattern having means engaging the locking member on said heating unit to be locked therewith and to hold said conical member fixed with respect to said heating unit.

2. A device for stretching or shaping spectacle rims, comprising a forming member formed of a plurality of segments hingedly connected to each other to permit shaping of same, a heating unit 65 on which said forming member is positioned and having a locking member, a pattern positioned on said forming member to shape same, said pattern having means engaging the locking member to be locked therewith and to hold said forming member fixed with respect to said heating element.

3. A device for stretching or shaping spectacle rims comprising a segmental cone member formed of a plurality of segments hingedly connected to each other to permit shaping of said

cone, a jacket member formed of a thin flexible material and having a continuous wall and mounted on said segmental cone, a heating unit on which said segmental cone and jacket is placed, said heating unit having a locking connection, a pattern positioned on said jacket member to shape said jacket and segmental cone, said pattern having means engaging the locking connection to be locked therewith and hold said jacket and segmental cone member fixed with respect to said heating unit.

4. A device for stretching or shaping spectacle rims comprising a cone shaped member formed of a plurality of segments hingedly connected to each other to permit shaping of said cone, a heating unit having a cupped portion which has a slotted section, said cone adapted to be positioned in said cupped portion, a pattern positioned on said cone member for shaping same, said pattern having lugs engaging the slotted section for holding said cone secured to said heating unit.

5. A device for stretching or shaping spectacle rims comprising a cone shaped member formed of a plurality of segments hingedly connected to each other to permit shaping of said cone, a heating unit having an upstanding wall provided with a plurality of inclined slots, said cone adapted to be placed on said heating unit, a pattern positioned on said cone member for

shaping same, said pattern having a plurality of lugs inclined complementally to said slots to engage said slots and lock said cone to said heating unit.

5 6. A device for stretching and shaping spectacle rims comprising a cone shaped member formed of a plurality of segments hingedly connected to each other to permit shaping of said cone, a wire member secured inside said cone for urging the segments outwardly with respect to each other, and a jacket member mounted on said cone.
